We claim the ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is a top rear perspective view thereof;

FIG. 9 is a bottom rear perspective view thereof;

FIG. 10 is a right-side perspective view thereof; and,

FIG. 11 is a left-side perspective view thereof.

The broken lines in the figures show portions of the electronic device which form no part of the claimed design.
